(57) **CLAIM**

The ornamental design for an electrical contact, as shown and described.

DESCRIPTION

FIG. 1 is a front elevational view of an electrical contact showing our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a sectional view thereof taken along line A—A of FIG. 3;

FIG. 8 is an enlarged sectional view thereof taken along line B—B of FIG. 6;

FIG. 9 perspective view from an upper left side thereof; and,

FIG. 10 is a perspective view from an upper right side thereof.
